(57) **CLAIM**

The ornamental design for a seating unit, as shown and described.

DESCRIPTION

1. Chair
2. Couch
- 1.1 : Perspective
- 1.2 : Front
- 1.3 : Back
- 1.4 : Top
- 1.5 : Right
- 1.6 : Left
- 2.1 : Perspective
- 2.2 : Front
- 2.3 : Back
- 2.4 : Top
- 2.5 : Right
- 2.6 : Left
- 2.7 : Reference

A new, original, and ornamental design for a seating unit, as set forth in the following specification. Views 1.1-1.6 show the claimed design in the form of a chair. Views 2.1-2.7 show the claimed design in the form of a couch. Fig. 2.7 is a reference view of a couch showing the new design in an environment of use. The heavy broken line are showing stitch lines in figs. 1.1-1.6 and figs. 2.1-2.7, while the light broken lines showing of portions of the seating unit in figs. 1.1-1.6 and figs. 2.1-2.7 form no part of the claimed design. The light broken lines in fig. 2.7 show portions of the seating unit and environment that form no part of the claimed design.

1 Claim, 13 Drawing Sheets
